TOY MERRY-GO-ROUND

Ernest R. Neyhard, Pottstown, Pa.

Application April 17, 1951, Serial No. 14,870

Term of patent 14 years

(Cl. D34—15)

To all whom it may concern:

Be it known that I, Ernest R. Neyhard, a citizen of the United States, residing at Pottstown, in the county of Montgomery and State of Pennsylvania, have invented a new, original, and ornamental Design for a Toy Merry-Go-Round, of which the following is a specification, reference being had to the accompanying drawing, forming part thereof.

Figure 1 is a perspective view of a toy merry-go-round, showing my new design, and

Figure 2 is a perspective view thereof, viewed from a direction opposite to that in Figure 1.

The essential features of my design reside in those portions shown in full lines.

I claim:

The ornamental design for a toy merry-go-round, as shown and described.

ERNEST R. NEYHARD.
